UNITED STATES PATENT OFFICE.

FRANK O. HOAGLAND, OF BRIDGEPORT, CONNECTICUT.

PROJECTILE.

1,111,459.

Specification of Letters Patent.

Patented Sept. 22, 1914.

Application filed January 8, 1914. Serial No. 810,101.

To all whom it may concern:

Be it known that I, FRANK O. HOAGLAND, a citizen of the United States, residing in Bridgeport, in the county of Fairfield and State of Connecticut, have invented certain new and useful Improvements in Projectiles, of which the following is a specification.

This invention relates to that class of projectiles which are usually made of elongated form and for use in small arms, and especially to such projectiles having a soft metal core with an elongated point incased in a tip-casing or point-cap.

A principal object of my present improvements is to furnish an improved anchorage or interlocking construction as between the point-cap and the soft metal core, one particularly designed for use in elongated projectiles of the so-called "mushrooming" class.

In the accompanying drawing, forming a part of this specification, Figure 1 is a side elevation of a projectile made in accordance with my present improvements, and showing the projectile provided with a main-core case, H, extending forwardly (toward the right hand) to a position about midway of the point-portion of the core, and with a point-cap or jacket-tip, P, secured on the point of the core. Fig. 1^a is a fragmentary view similar to the right-hand portion of Fig. 1, for showing a variation in the outline form of the opening, 5, in the wall, t, of the point-cap P. Fig. 2 is a view similar to Fig. 1, but shows the projectile as seen from below in Fig. 1, and with some parts broken away to show the tip portion in longitudinal section. Fig. 3

is a view similar to Fig. 2, but showing the point-cap P extending rearwardly outside of the reduced forward end of the main core-casing, H, whereas in Figs. 1 and 2, there is shown a narrow zone of core-metal, 9, located between the separated edges, 2 and 3, of said core-incasing members H and P, respectively. Fig. 3^a illustrates a modification in the anchor device arrangement. Fig. 4 is an enlarged sectional view,—of a diagrammatic character,—of a preferred form of the point-cap, but with some portions omitted. Fig. 5 is an end elevation of that portion of the point which is shown in Fig. 4, as seen from the right-hand of said figure. Fig. 6 is a sec-

tion on line Z—Z, Fig. 4, showing the parts at the right-hand of said line as seen from a point at the left-hand thereof.

Similar characters represent like parts in all of the views.

In projectiles having incased soft-metal cores and formed with elongated points, and owing partly to the usual increase of the tangent-angle (of the curve of the point-cap surface) toward the apex of the nose or point, a point-cap or tip-casing made of the thin metal sometimes used therefor, is not held in place with sufficient security by core-projections or plugs which simply extend outwardly into corresponding perforations in such a point-cap. This objection is especially important when such openings are located relatively near to the extreme tip-end or apex of the projectile point. The limited coaction of such openings and projections is diagrammatically illustrated in Fig. 4, in which 8 is the longitudinal axis of the projectile, the point-cap P being shown in section and having therein the opening 5 located in a position where the cap-wall t is sharply inclined to said axis line 8. A line 10 is drawn parallel to the axis 8 for showing how very small an amount of core-metal,—as indicated by the small shaded area at d,—operates as a 85 detent or lock forward of the narrow cap-wall edge e, for holding the cap P upon the core point C'; and it will be evident that when the core is of lead or of soft alloy, such holding power will be too slight for 90 effective use with point-caps made with a very thin wall. For overcoming these limitations and objections, I have devised the anchorage means which will now be more fully explained.

At the forward edge of an opening, as 5, in the cap-wall t, I provide an inwardly extending anchor, as N, which, in the preferred form thereof herein shown, is in the nature of a wall or blade and is so located and shaped as to be adapted for being made by the turning inwardly of the metal, or a portion thereof, which is removed for forming the said opening. This construction, as will be evident, has the advantage of utilizing wholly, or in part, the metal which would otherwise be removed, and of providing such an anchorage device or blade which shall be integrally connected for a considerable distance around one side (usually the forward

side) of the opening 5 with the wall of the point-case; this integral juncture of said wall, *t*, and said anchor device *N* is indicated at 6, Fig. 4. A further feature of the anchor device, when thus arranged and located, is the transverse curvature or the angular form which it has relatively to a geometric plane transversely of the axial line 8, as will appear obvious from a comparison 10 of the several views, particularly the diagram Figs. 4, 5 and 6. This transverse formation of the said anchorage blade *N* is a braced-construction, whether curved, as in the principal views, or angular, as in Fig. 15 1^a, and in both cases conformed to the forward side of the opening 5. In Fig. 1^a this opening is of non-curved outline, and the angular and braced formation of the metal along that line operates to stiffen both the 20 wall, *t*, and the anchorage member *N*; and especially to stiffen the anchorage member as against the pressure of the flowing core-metal when the projectile is subjected to the usual operation of swaging in a die for 25 bringing it to final shape. During this operation the position of the anchorage blade *N*, especially when it is set in an inclined position, as indicated by the line *r*, tends to direct or deflect a portion of the flowing core- 30 metal outwardly, as indicated by the arrow *n*, Fig. 4, and thereby more certainly entirely fill the said opening or perforation 5. When the anchor blade *N* is being thus embedded or immersed edgewise thereof into 35 the core by the pressure of the swaging operation, the initial action naturally tends, to some extent, to displace and deform the said anchor member, this tendency being resisted, however, by the inclined position and also by 40 the transversely curved or the angular formation, as the case may be. When the core metal is thus flowed out to fill the openings 5 and form the projections 7, these projections constitute parts which on one surface 45 engage with an anchorage device, and on the opposite side engage with the edge-surface of said cap-wall openings.

One advantage of a point-cap fastening of the character herein set forth is the normal 50 tendency of the pressure upon and around the extreme tip of the projectile, especially when this strikes a yielding target, to hold the middle portion of the point-cap in interlocked engagement with the point portion 55 of the core until after this part is considerably deformed and the rearward end of the cap is much enlarged by reason of the flowage of the core-metal.

In Fig. 3^a one of the anchorage devices, *N*, 60 is shown located forward of the opening 5, while another said device *N'*, is shown located rearwardly of the adjacent opening 5'. In practice, any one or more of a series of the anchorage devices,—or all of them, if desired,—may be arranged in the same man-

ner as the anchorage *N'*, but for use in projectiles of the smaller sizes and more usual proportions, I deem the other arrangement to be preferable, especially in "mushroom" projectiles. The point-cap, however, with 70 either said arrangement of anchorage device, is adapted to be used on projectiles other than the mushrooming or expandable kind, and to be used either with or without a separate body-jacket or casing located on the 75 body of the core rearwardly of the point-cap.

Owing to the inclination and location of the anchorage device, *N*, in each of the specific arrangements set forth (as *N* and *N'*), this device extends edgewise thereof within 80 the mass of the core-metal by which said device is thus surrounded and included. Thus the anchorage device consists of a portion of the cap-wall bent or turned inwardly at such an angle that this turned-in and single-thickness portion is plunged edgewise into 85 the core, and is bodily immersed therein. And owing to this organization of the component features, the action of the two different kinds of retaining-devices, as 7 and *N*, 90 respectively, (when the two are employed together) is supplemental, the one to the other. The exuded core-projections 7 act prior to and during only the early stage of 95 the deformation of the projectile, while the action of the anchorage devices *N* continues for a time after the cap-retaining engagement of said projections 7 has been destroyed, and until the deformation of the 100 projectile-point has proceeded well toward the end of the later state thereof. While the modes of action of those two kinds of retaining devices and also their periods of action, are materially different from each other, the devices themselves, in the described combination, are directly co-operative with and complementary to each other.

Having thus described my invention, I claim:

1. In a projectile having a soft metal core 110 with an elongated point portion, the combination with the core, of a point cap having a thin metal wall with one or more openings therein, projections extending outwardly from the core and filling said openings, and an anchorage device integrally connected with the metal wall contiguous to the openings and extending inwardly therefrom and immersed within the metal of the core whereby the interlocking of the projections 115 with the point-cap wall is supplemental to and reinforces the interlocking of the same by the anchorage device.

2. In a projectile having a soft metal core 125 with an elongated point portion, the combination with the core, of a point cap having a thin metal wall with one or more openings therein, and an anchorage device integrally connected with the metal wall contiguous to an opening and extending inwardly there- 130

from and embedded edgewise thereof within the core metal which surrounds and encloses the anchorage device.

3. In a projectile of the class described, the combination with a soft metal core, of a point-cap having a thin metal wall with one or more openings therein, cap-retaining projections extending outwardly from the core and filling the said openings, and an anchorage device contiguous to one side of an opening and extending inwardly therefrom and immersed within the metal of the core, whereby the interlocking of the projections with the point-cap is supplemental to and reinforces the interlocking of the same by the anchorage device.

4. In a projectile, in combination, a soft metal core, a point-cap having a thin metal wall with one or more openings therein, projections extending outwardly from the core and filling the openings, and an anchorage device extending inwardly from the metal wall and contiguous to the forward side of an opening, and immersed edgewise thereof into the core metal, substantially as described.

5. In a projectile having a soft metal core with an elongated point portion, the combination with the core, of a point-cap having a metal wall with one or more openings therein and having one or more anchorage devices each projecting inwardly from the point cap wall and immersed in the core metal and located adjacent to the one edge of an opening.

6. In a projectile having a soft metal core with an elongated point portion, the combination with the core, of a point-cap having a metal wall with one or more openings therein and having one or more anchorage devices each projecting inwardly from the point cap wall and immersed in the core metal and each located adjacent to the forward edge of an opening.

7. In a projectile having a soft metal core with an elongated point portion, the combination with the core, of a point-cap having in the wall thereof one or more openings and having one or more anchorage devices each projecting inwardly from and inclined rearwardly of the point-cap wall and immersed edgewise thereof in the core metal and each located adjacent to the forward edge of an opening.

8. In a projectile having a soft metal core, the combination with the core, of a point-cap having a wall with one or more openings therein and having one or more

anchorage devices each projecting inwardly from the point-cap wall and embedded edgewise thereof within the core metal and each located adjacent to one edge of an opening, and the core having projections filling the openings adjacent to the anchorage, whereby the interlocking of the projection and cap is supplemental to and reinforces the anchorage device.

9. In a projectile having a soft metal core, the combination with the core, of a point-cap having a wall with one or more openings therein and having one or more anchorage devices each projecting inwardly from the point-cap wall and inclined rearwardly from the point of the core and embedded edgewise thereof within the core metal and each located adjacent to the forward edge of an opening, the core having a projecting part engaging on one surface thereof with an anchorage device and on the opposite side with the edge surface of the cap-wall opening.

10. In a projectile having an elongated soft metal core, the combination with the core, of a point-cap having a metal wall with one or more openings therein and having one or more anchorage devices each projecting inwardly from the point-cap wall and embedded and inclosed edgewise thereof within the core metal and each located adjacent to one edge of an opening, said anchor devices being integrally connected with the metal wall and having a sectional form with a curvature transversely thereof and relatively to a plane transverse to the axis of the projectile whereby said anchor devices are stiffened and are braced as against dislocation.

11. In a projectile having an elongated soft metal core, the combination with the core, of a point-cap having a metal wall with one or more openings therein and having one or more anchorage devices each projecting inwardly from and inclined rearwardly of the point-cap wall and immersed edgewise thereof within the core metal and each located adjacent to the forward edge of an opening, said anchor devices being integrally connected with the metal wall and having a concaved construction, relatively to a plane transverse to the axis of the projectile.
